UNITED STATES PATENT OFFICE.

MILON VAL MILLER, OF CHICAGO, ILLINOIS.

UNDER-WATER EXHAUST.

1,073,920.

Specification of Letters Patent. Patented Sept. 23, 1913.

Application filed October 28, 1912. Serial No. 728,221.

To all whom it may concern:

Be it known that I, MILON VAL MILLER, a citizen of the United States, residing at Chicago, in the county of Cook and State 5 of Illinois, have invented certain new and useful Improvements in Under-Water Exhausts; and I do declare the following to be a full, clear, and exact description of the invention, such as will enable others skilled 10 in the art to which it appertains to make and use the same.

This invention relates to internal combustion engines, and more especially to the exhaust treatment thereof; and the object of 15 the same is to provide an exhaust for outboard gasolene engines such as are clamped over the stern of a launch, which exhaust will convey the gases from the engine to a point beneath the water level so as to muffle 20 the sound of the pulsations, avoid smoke and odors, and produce suction on the exhaust pipe by disposing its outlet end just in advance of the propeller, meanwhile making provision for opening a relief in the exhaust 25 when desired.

These objects are carried out by constructing the under water exhaust in a manner hereinafter more fully described and claimed, and as shown in the drawings 30 wherein—

Figure 1 is a general perspective view of the rear end of a boat in outline with the "Evinrude" motor attached, showing the adaptation of my invention thereto. Fig. 2 35 is an enlarged rear elevation of my exhaust removed from the motor and boat, the same being shown partly in section. Fig. 3 is a central vertical sectional view throughout the length of the exhaust, on the line 3—3 40 of Fig. 2. Fig. 4 is a detail of the outlet end of the exhaust showing the notch in the bottom thereof.

In the drawings the letter B designates a launch or other boat, to whose stern in the 45 present instance is attached a framework F carrying a motor M from which depends a sleeve S through which power is transmitted to the propeller P, and the exhaust of the motor is roughly indicated at E. The object of the present invention is to convey 50 the exhaust gases from the point E to a point below the water level and just in advance of the propeller P, whereby the rotation of the latter will create suction on the 55 exhaust so as to facilitate the running of the engine, and the fact that the exhaust gases

are discharged below the water level will deaden the noise thereof and suppress the smoke and odor rising therefrom.

Coming now more particularly to the present invention, shown in the embodiment herewith as applied to a sleeve S which it will be observed is telescopic in the Evinrude motor so that the propeller P can be set at the desired elevation according to the build of the boat B, my exhaust consists of a pipe made also telescopic in order that it may be lengthened as the sleeve S is lengthened or shortened as the sleeve is reduced in length. This pipe has an upper section 1 over which telescopes a lower section 2, the sections being connected by any suitable means such as a clamp 3 which may be tightened up after adjustment and which possibly may serve as one of the means of supporting the device; the lower section 2 passes through another clamp 4 which in the present instance engages the sleeve S as shown, and its lower end is turned to the rear into an elbow 5 whose outlet end 6 stands just in front of the propeller P and whose lower side is notched in V-shape as seen at 7. The upper end of the upper section 1 is connected in any suitable manner, as by the clamp 8, with the exhaust E of the motor M. It follows that when the motor is started running, the exhaust gases are conveyed down through the sections 1 and 2, and by the elbow 5 are turned to the rear and delivered out through the end 6 directly toward and close in front of the propeller P so that the rapid rotation of the latter creates a partial vacuum within the elbow and therefore sucks on the gases therein and a draft is produced throughout the length of the exhaust while the propeller is running. The presence of the notch 7 in the bottom of the rear end of the elbow also assists in setting up the suction referred to, because while the boat is traveling forward 100 the rearward movement of the water through this notch adds to the suction downward which is set up throughout the length of the exhaust.

In the adaptation of my invention to the Evinrude motor as illustrated, it becomes necessary to put elbows 10 and 11 in the upper section 1 so that the upper end thereof will stand a little to one side of and out of alignment with the lower end and with the lower section 2, and the upper extremity of the upper member can be clamped at 8

to the exhaust E of the motor. It will be clear that when this device is applied to other types of motors, these elbows 10 and 11 may be emphasized, otherwise disposed, 5 or in some instances possibly omitted; but the purpose in providing them is to cause the upper extremity of the upper section to connect with the motor exhaust E, and the length of the lower section to follow the 10 sleeve S or whatever other portion of the framework supports the drive shaft for the propeller P so that the outlet end 6 of the lower section shall stand strictly in front of the propeller blades.

15 An amplification or refinement of my invention consists in providing one of the sections at a suitable point with a relief opening 12 herein shown as produced by cutting away one side of the upper section 1, 20 and this opening is adapted to be closed or opened at the will of the operator. In the present instance I have shown the closure as consisting of a collar 13 slidably inclosing the upper section 1 and adapted to be 25 moved so as to expose the opening 12 as shown in Fig. 2 or to close the same as shown in Fig. 3, the collar in this instance being surrounded by a clamp 14 which may be tightened by means of a set screw 15 30 through its arms and both standing within reach of the operator. With the set screw adjusted moderately tight the operator can grasp the clamp 14 and slide the collar upward or downward, thus closing or opening 35 the relief 12 at will; or he may tighten the set screw when the collar stands over the relief, and the exhaust pipe will then be complete from the exhaust E to the outlet end 6 of the lower section. Any other suitable 40 means may be provided for producing a relief within the exhaust, the obvious purpose of which is to open it into the air when the operator desires to start or speed up the engine, or when he wishes to signal or to 45 ascertain if the exhaust contains carbon deposits.

I do not wish to limit myself to the exact details of construction, and the relief may be added or not as desired. It is quite obvious 50 that the elbows 10 and 11 are only to be employed when the shape of the motor and its framework require. The sizes and materials of parts are not essential to the present invention.

55 What is claimed as new is:

1. The combination with a boat, a motor, an upright framework detachably connected with the stern of the boat, an upright sleeve carried by the framework, and the propeller 60 at the lower end of said sleeve; of an exhaust pipe connected at its upper end with the exhaust of the motor, its body led downward alongside said sleeve, and its lower end having an elbow whose outlet end is

directed rearward toward and stands close 65 to the propeller so that rotation thereof sets up suction in said pipe and means for clamping said pipe to said sleeve.

2. The combination with a boat, and a motor therefor including a framework 70 clamped to the stern of the boat, an upright carried by the framework, and the propeller at the lower end of said upright; of an exhaust pipe connected at its upper end with the exhaust of the motor, its body led downward alongside said upright, and its lower end having an elbow whose outlet end is 75 directed rearward toward the propeller, the pipe being made in sections telescoping on each other, a clamp for holding the sections 80 after they are adjusted, and clamps for connecting said sections with the framework and upright.

3. The combination with a boat, and a motor therefor including a framework 85 clamped to the stern of the boat, an upright sleeve carried by the framework, and the propeller at the lower end of said sleeve; of an exhaust made in two sections whose meeting ends are telescopically mounted 90 upon each other, a clamp for holding said ends after they have been adjusted, the upper end of the upper section being connected with the motor-exhaust and the lower end of the lower section being directed to 95 the rear in front of the propeller, means for connecting said sections with the framework and sleeve; the upper section being provided with a relief opening, and means for closing the latter at will.

4. The combination with a boat, and a motor therefor including a framework clamped to the stern of the boat, an upright carried by the framework, and the propeller at the lower end of said upright; of an exhaust made in two sections whose meeting ends are telescopically mounted upon each other, a clamp for holding said ends after 105 they have been adjusted, the upper end of the upper section being connected with the motor-exhaust and the lower end of the lower section being directed to the rear in front of the propeller, means for connecting said sections with the framework; the upper section having elbows within its length 110 throwing its upper extremity out of alignment with the lower section and also being pierced with a relief opening between said elbows, a collar slidably mounted on this section between its elbows and adapted to 115 be moved over said opening, a clamp surrounding said collar, and a set screw through the clamp arms, for the purpose set forth.

5. The combination with a boat, and a motor therefor including a framework 125 clamped to the stern of the boat, an upright carried by the framework, and the propeller at the lower end of said upright; of an ex-

haust made in two sections whose meeting ends are telescopically mounted upon each other, means for holding said sections after they have been adjusted, the upper end of 5 the upper section being connected with the motor-exhaust and the lower end of the lower section being directed to the rear, means for connecting said sections with the framework, the upper section having a 10 relief opening, and a collar slidably mount-

ed on this section and adapted to be moved over said opening, for the purpose set forth.

In testimony whereof I have hereunto set my hand in presence of two subscribing witnesses.
